CLAIM

The ornamental design for a folding keyboard and display unit, as shown and described.

DESCRIPTION

FIG. 1 is a perspective view of a folding keyboard in a folded state showing our new design.

FIG. 2 is a top plan view of the design shown in FIG. 1.

FIG. 3 is a right-side elevation view of the design shown in FIG. 1.

FIG. 4 is a perspective view of the design shown in FIG. 1 in a partially unfolded state.

FIG. 5 is a perspective view of the design shown in FIG. 1 in an unfolded state.

FIG. 6 is a front elevation view of the keyboard shown in FIG. 5.

FIG. 7 is a rear elevation view of the keyboard shown in FIG. 5.

FIG. 8 is a right elevation view of the keyboard shown in FIG. 5.

FIG. 9 is a left elevation view of the keyboard shown in FIG. 5; and,

FIG. 10 is top plan view of the keyboard shown in FIG. 5.
